UNITED STATES PATENT OFFICE

146,898

DESIGN FOR A HANDLE FOR SCREW- DRIVERS AND THE LIKE

Elmer H. Daniels, Pasadena, Calif., assignor to
The Plomb Tool Company, Los Angeles, Calif.,
a corporation of California

Application February 25, 1946, Serial No. 127,208

Term of patent 14 years

(Cl. D93—4)

To all whom it may concern:

Be it known that I, Elmer H. Daniels, a citizen of the United States of America, residing in the city of Pasadena, in the county of Los Angeles, State of California, have invented a new, original, and ornamental Design for a Handle for Screw-drivers and the like, of which the following is a specification, reference being had to the accompanying drawings, forming a part thereof.

Fig. 1 is an elevational view of a handle showing my new design;

Fig. 2 is an elevational view thereof in an aspect of right angles to Fig. 1;

Fig. 3 is a section on line 3—3 of Fig. 1;

Fig. 4 is a section on line 4—4 of Fig. 1; and
Fig. 5 is a perspective view thereof.

I claim:

The ornamental design for a handle for screw-drivers and the like, substantially as shown.

ELMER H. DANIELS.
